DISK PLOW

Herman G. Klemm, Birmingham, and Noral A. Nelson, Royal Oak, Mich., assignors to Harry Ferguson, Inc., Detroit, Mich., a corporation of Delaware

Application April 11, 1949, Serial No. 1,896

Term of patent 14 years

(Cl. D39—1)

To all whom it may concern:

Be it known that we, Herman G. Klemm, a citizen of the United States, residing at Birmingham, in the county of Oakland, and State of Michigan, and Noral A. Nelson, a citizen of the United States, residing at Royal Oak, in the county of Oakland, and State of Michigan, have invented a new, original, and ornamental Design for a Disk Plow, of which the following is a specification, reference being had to the accompanying drawing, forming a part thereof.

Fig. 1 is a side elevation of a disk plow, embodying our new design;

Fig. 2 is a plan view of the plow of Fig. 1; and
Fig. 3 is an end elevation of the plow of Fig. 1.

The dominant feature of the design of the present invention resides in the portions shown in full lines in the accompanying drawings.

We claim:

The ornamental design for a disk plow, substantially as shown and described.

HERMAN G. KLEMM.
NORAL A. NELSON.
